UNITED STATES PATENT OFFICE.

ALBERT E. JOHNSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON SOLES.

1,307,820.

Specification of Letters Patent. Patented June 24, 1919.

Application filed September 25, 1916, Serial No. 122,076. Renewed October 18, 1918. Serial No. 258,758.

To all whom it may concern:

Be it known that I, ALBERT E. JOHNSON, a citizen of the United States, residing at Beverly, in the county of Essex and State 5 of Massachusetts, have invented certain new and useful Improvements in Machines for Operating on Soles; and I do hereby declare the following to be a full, clear, and exact description of the invention, such as will

enable others skilled in the art to which it appertains to make and use the same.

This invention relates to machines for operating on the marginal portion of soles, and more particularly to machines for off-setting the marginal edge of turn soles. The 15 latter operation is known as turn sole molding.

The operation of turn sole molding is performed for the purpose of properly presenting the shoulder to the needle of the inseam sewing machine. Remembering that the area of the bottom of a last for turn soles is less than the area of the sole of the shoe to be made on the last, it will be observed that the molding of the edge must be along a line determined with some nicety if the molded sole is to properly fit the last. As the edge of the last follows the line of the shoulder it is obvious that the angle of the molded edge should come on the grain side just opposite the shoulder, in which event the sole lies flat on the last bottom with its feather bent at an angle over the last-edge with the shoulder nicely opened up to receive the inseam stitches. Should the angle referred to be so formed that it lies within the edge of the last, much of the mold is taken out in the performance of the lasting operation which flattens the sole 30 down on the last. As a result of this improper molding, at the time the inseam is secured the shoulder is in much the same position relative to the feather that it was before the molding operation and the inseam sewing operator has great difficulty in keeping the needle from striking through the edge of the sole, which disaster, in spite of his efforts, frequently takes place.

One object of the present invention is to 50 hold and operate on the sole as it advances through the molding machine that the disadvantages of the prior machines are overcome, thus insuring an accurate fitting

of the sole on the last and a retention of the molded offset after lasting. In accordance 55 with this object a feature of the invention contemplates the provision of novel means for holding the sole rigidly in position between the molding rolls so that the angle formed by the offset of its margin may be 60 continuously and accurately spaced from its edge.

The turn sole molding machines now used commercially have another serious disadvantage which often results in breaking the 65 grain. This is due to a shifting of the sole relatively to the molding rolls during the feed of the sole through the machine resulting from the insecure grip which the rolls have on the sole, and a too heavy pressure 70 applied to the molding rolls used in an endeavor to overcome this defect.

Another object of the invention is to overcome the marring of the sole bottom due to grain breaks and the like which can later be 75 eradicated only by scouring down through the depth of the break. In accordance with this object a feature of the invention contemplates the provision in the machine of a novel arrangement of the parts for feeding 80 the sole which provides for a feeding grip on the edge of the sole and permits a lightening of the injurious pressure heretofore used.

The invention further improves existing 85 sole molding machines by so arranging the molding and sole feeding rolls that the edge of the sole is maintained at its full thickness, the full depth of the shoulder is preserved, and the channel is properly opened 90 for the reception of the inseam, all as will be made clear from the following description.

If the turn sole is to be reinforced, in the manner disclosed and claimed in my prior 95 Patent No. 1,200,114, October 3, 1916, the manner in which the channel is opened is of particular importance. For reinforced work care must be taken to set the flap in such a position that its tendency to drop 100 toward its original position in the channel is overcome. Otherwise in applying the sticky reinforcing fabric it adheres to the outer surface of the flap and prevents the tools of the reinforcing machine from working the fabric down into the channel. The

sole should be so fitted that the inner surface of the flap, and not its outer surface, is exposed to the reinforcing fabric, leaving the channel well opened to receive the reinforcing tools. A feature of the present invention insures that the flap will be opened and set in a position curled outwardly toward the margin of the sole to expose its inner surface.

10 To the accomplishment of these objects and such others as may hereinafter appear, as will readily be understood by those skilled in the art, the invention comprises the features and combinations of parts hereinafter described and particularly pointed out in the appended claims.

15 In the accompanying drawings, illustrating the preferred form of the tools for operating on the marginal portion of the sole, 20 the said tools are shown applied to the sole molding machine of Letters Patent to E. S. Harris, No. 343,453, dated June 8, 1886. In said drawings, Figure 1 shows a longitudinal, vertical section of the said Harris machine, with the present improvements embodied therein; and Fig. 2 shows a side elevation of the improved tools in detail, with a sole between them.

25 In the illustrated embodiment of the invention the particular type of turn sole 10, used for illustrative purposes, is produced by passing a tempered blank through a channelling machine, such as is illustrated and described in United States Letters Patent to William C. Meyer, No. 984,773, dated 30 February 21, 1911, said machine being first provided with suitably shaped knives. This turn sole forms the subject-matter of my co-pending application Serial No. 669,568, filed 40 January 5, 1912, patented October 3, 1916, No. 1,200,114 of which the present application is a continuation in part.

45 The channeled blank is then passed through my novel molding and lip setting machine illustrated in said patent and in the accompanying drawing, to offset, or bend back, its marginal portion. This machine is provided with a set of coöperating molding rolls comprising a sole supporting and bending roll 12, a channel flap opening roll 14, and an edge molding roll 16.

50 Referring to Fig. 1 illustrating the construction of said Harris machine, the channel flap opening roll 14 is secured to the forward end of a shaft 26 which is journaled in a horizontal arm 28 pivoted at its rear end to the machine frame 30. The edge molding roll 16 is secured to the forward end of a second shaft 32, parallel to the shaft 26 and journaled in the frame 30 below the pivoted arm 28. Power for rotating said shafts is applied through a large gear 36, journaled on a stud 38 in the frame, which meshes with a smaller gear 40 on the rear 55 end of the shaft 32. The shaft 26 is driven

from the shaft 32 by intermeshing gears 42 and 44, one on each shaft. These gears are preferably so proportioned as to drive the setting and edge molding rolls at the same peripheral speed, but said rolls may have 70 different peripheral speeds. The gear 36 is shown as rotated by a hand crank 46, although power means may be used if desired.

75 While operating the machine the pivoted arm 28 is held down, so that considerable pressure is exerted on the sole by the tool 14, by a spring 48 mounted in the manner illustrated, on a rod 50 which depends from the arm and passes through a bore in the lower 80 part of the frame. Pressure is also exerted on the grain face of the sole by the sole supporting and bending roll 12 which is rotatably mounted in the upper end of a vertical arm 52, pivoted at its lower end on the 85 frame. This arm is held yieldingly toward the rolls 14 and 16 by an expansion spring 54, seated in a socket in the frame and exerting pressure on a collar at the inner end of a rod 56 connected, at its outer end, to the 90 arm 52. A stop 58 may be mounted in the frame to limit the inward movement of the tool 12 when no work is in the machine.

95 The tools may be separated to enter and remove soles by moving the arms 28 and 52 upwardly and outwardly, respectively, about their pivots. To this end a push rod 60 is 100 slidably carried in the frame, its forward end abutting against the arm 52 and its rear end adapted to be engaged by a pusher 62, pivoted on the frame, having an arm bearing on the upper side of a collar 64 on the rod 50. A lever 66, centrally pivoted on the frame, bears with its forward end beneath a transverse pin 68 in the rod 50 and has a 105 treadle rod 70 attached to its rear end. On depressing the treadle (not shown) attached to the treadle rod 70, the rod 50 is raised, against the force of the spring 48, which lifts the arm 28. At the same time the 110 pusher 62 is actuated to advance the push rod 60 and swing the arm 52 outwardly against the force of the spring 54. On releasing the treadle the springs 48 and 54 return the rolls 14 and 12 to operating position 115 relative to the roll 16, as shown in Fig. 2.

120 The bending roll 12 has a circumferential face that engages the grain side of the sole near its marginal edge, the longitudinal curvature of which may be modified for any desired extent of bending, or dishing, of the sole. The channel flap roll 14 engages the channel of the sole opposite the roll 12 and acts to compress the sole against the roll 16. The edge molding roll 16 for the type of turn sole illustrated, has an edge compressing face 18, a feather engaging face 20, a shoulder forming face 22, and a lip or shoulder setting face 24. As already described, the roll 16 is rigidly mounted in 125 130

the machine frame while the rolls 12 and 14 are pressed toward the roll 16 by means of springs. With this construction the marginal portion of the sole is pressed by the 5 rolls 12 and 14 against the different faces of the edge molding roll 16, the edge of the sole being pressed into the angle formed between the edge face 18 and the side faces 20, 22 and 24. This angle, in conjunction 10 with the angle on the face of the roll 12, determines the shape and location of the offset edge formed on the sole.

As illustrated, the rolls 14 and 16 are constructed to open the channel and set the 15 flap in the manner required for reinforced work. The channel flap roll 14 is provided with a head 13, preferably of disk form, which enters the channel and acts as a plow. Just back of the head 13 the neck 15 of the 20 roll is of smaller diameter providing a concave formation which rolls the flap outwardly to expose its inner surface. The edge molding roll 16 is provided with a convex surface 17 complementary to the curve 25 of the neck 15, preferably in the form of a circumferential bead. The bead 17 is formed at the end of the shoulder setting face 24 and bears on the outer surface of the flap. The coöperative action of the roll constructions just described causes the flap to be 30 molded to a position curled outwardly away from the channel, leaving the channel exposed for the application of reinforcing fabric, as shown in Fig. 7 of said Patent No. 35 1,200,114, October 3, 1916.

During the edge molding operation the margin of the sole is compressed longitudinally between the face 18 of the roll 16 and the roll 14, and also transversely between 40 the roll 12, and the roll 14 and the faces 20, 22 and 24 of the roll 16. By this combined compression the bent fibers of the sole are so set that the molded shape becomes permanent until, after having been applied 45 to the shoe, the sole is to be beaten out. Due to the peculiar configuration of the molding faces of the rolls 12, 14 and 16, and their grip on the sole, the edge may be offset with a moderate pressure. As a result, the more 50 or less sharply curved face of the supporting roll 12 does not break the grain face of the sole as hereinbefore mentioned.

The edge compressing face 18 of the roll 16 is preferably, although not necessarily, 55 provided with serrations which act to grip and feed the sole during the molding operation. It will be noted that the edge of the sole is rigidly held between the rolls 12, 14 and 16, so that if the edge is thin it will 60 be supported with sufficient rigidity to enable the serrations on the face 18 to feed it. In this manner a sole with a thin feather may be efficiently fed by its edge and at the same time the compression of the sole edge 65 against the face 18 assists in molding it.

While the edge compressing face is preferably serrated to assist in feeding the sole, it will be found in practice that the pressure alone of the molding rolls will act to feed many types of soles.

While the machine as illustrated in the drawing is particularly adapted for offsetting the edge and setting the feather lip of a particular type of turn sole, the invention is not limited to treating this type of sole, 70 but is equally well adapted for treating other types of soles including regular turn soles or solid and reinforced insoles. Similarly the device for feeding the sole by engagement with its edge may also readily be 80 applied to other sole fitting machines for performing such operations as lip setting, reinforcing or channeling.

The nature and scope of the invention having been indicated and the preferred 85 form of the invention having been specifically described, what is claimed as new is:

1. A machine for offsetting the marginal portion of soles, having, in combination, co-operating molding rolls for engaging opposite sides of the sole near its margin; a roll 90 having angularly arranged faces for engaging one side and the edge of the sole; means for pressing said rolls together to mold the sole into the angle formed by said faces; 95 and means for driving the rolls.

2. A machine for offsetting the marginal portion of soles, having, in combination, a fixed edge molding roll having angularly arranged faces, one for engaging a side and 100 the other for engaging the edge of the sole; a movably mounted bending roll for operating on the side of the sole opposite the side engaging face of the edge molding roll; a movably mounted channel pressing roll opposite the edge engaging face of the edge molding roll; and means for pressing the bending and channel rolls toward the faces of the edge molding roll to offset the sole 105 edge.

3. A machine for operating on the marginal portion of soles, having, in combination, coöperating rolls for treating the marginal portion of the sole; and means acting on the edge of the sole to advance the 115 sole through the machine.

4. A machine for operating on soles, having, in combination, coöperating sole pressing rolls for treating the marginal portion of soles, one of said rolls being constructed 120 and arranged to operate on the edge of the sole for feeding the sole during the treating operation; and means for driving the rolls.

5. A machine for operating on the marginal portion of soles, having, in combination, coöperating molding rolls for engaging opposite sides of the sole near its margin, one of said rolls being constructed and arranged to engage and compress the edge of 125 the sole, the face of the latter roll in contact 130

with the sole edge being roughened so that it will act to feed the sole; and means for driving the rolls.

6. A machine for molding turn soles, having, in combination, a channel flap opening roll, a sole supporting and bending roll, an edge molding roll, having an edge compressing and sole feeding face, and means acting through one of said rolls for pressing the sole against said face of the edge molding roll.

7. A machine for molding channeled turn soles, having, in combination, coöperating rolls for engaging the margin of the sole at opposite sides of the channel flap, said roll at the outer side of the flap having a portion engaging the edge of the sole, and means acting through one of said rolls for exerting pressure on the sole stock held between said rolls.

8. A machine for molding channeled turn soles, having, in combination, an edge molding roll having three faces for engaging the shoulder, the feather, and the edge of the sole, and means for holding the sole under pressure in contact with all of said faces.

9. In a machine for operating on the marginal portion of soles, coöperating sole pressing rolls for operating on said margin; one roll being provided with a head which enters the channel to open the flap and with a concaved neck, of smaller diameter than the head, within which the flap is rolled; and the other roll being provided with a circumferential bead which enters the curve of said neck and molds the flap therein, causing it to be set in a position curled outwardly toward the margin of the sole.

10. In a machine for operating on the marginal portion of soles, coöperating sole pressing rolls for operating on said margin; one roll being provided with a circumferential projection, in the form of a narrow bead,

which bears on the outer side of the channel flap; and the other roll being provided with a circumferential depression, complementary to the bead, which bears on the inner side of the channel flap, the coöperative action of said rolls being to mold the flap in a position curled outwardly away from the channel.

11. In a machine for operating on the margin of a channeled sole, said channel being produced by a downward and outward cut, a pair of rolls for operating on said margin, said rolls having complementary convexly and concavely curved circumferential surfaces which engage the outer and inner sides of the channel flap respectively and coöperate to mold said flap on a curve turned outwardly toward the margin of the sole.

12. A machine for operating on the marginal portion of soles provided with a channel flap produced by a downward and outward marginal cut having, in combination, a flap setting roll having a concave circumferential face arranged to engage the inner surface of the flap and curl it outwardly toward the margin of the sole, means engaging the outside of the flap coöoperating with said roll to set the flap in such position, and means for supporting the sole with its flap between said coöperating members.

13. A machine for operating on the marginal portion of soles provided with a channel flap produced by a downward and outward marginal cut having, in combination, coöperating flap-setting members engaging the inner and outer surfaces of the flap constructed and arranged to mold the flap into a position curled outwardly away from the channel, and means for supporting the sole with its flap between said flap-setting members.

ALBERT E. JOHNSON.
